UNITED STATES PATENT OFFICE

GEORGE R. METCALF, JR., OF ERIE, PENNSYLVANIA, ASSIGNOR TO ERIE MALLEABLE IRON COMPANY, OF ERIE, PENNSYLVANIA, A CORPORATION OF PENNSYLVANIA

LIGHTING FIXTURE

Application filed February 25, 1928. Serial No. 256,849.

The light fixture is particularly designed to provide a lighting scheme for power pole lines, one of the uses of such lighting system being as a protection in aviation. The invention involves forming such an integral fitting that will make the necessary mounting and connection for such a light. Details and features of the invention will appear from the specification and claims.

10 A preferred embodiment of the invention is illustrated in the accompanying drawings as follows:—

Fig. 1 shows a perspective view of the mounting in place.

15 Fig. 2 a front elevation, partly in section. 1 marks the line post and 2 the power line wires which it is desired to indicate. The post is extended by strips, or bars 3 on which a cross piece 4 is mounted, these cross pieces 20 carrying lighting wires 5.

The light fixture comprises a head 6 which is hollow and has the internal flange 7 forming a base for receiving a light socket 8, the light socket being secured to this base preferably on a gasket 7^a by screws 9, the light socket carrying the usual incandescent light 10.

A globe 11 is secured in the head 6, the head and globe being ordinarily provided 30 with screw threads by which the globe may be secured, the globe seating on the gasket 7^a.

An opening 13 is arranged within the seat 7 through which the light wires may be led from the lamp socket and a conduit sleeve 14 35 is formed integrally with the head and extends therefrom. A high ring 6^a is arranged in the head around the opening to the conduit 14 and the head is provided with drain openings 6^b and 6^c to take care of any leakage 40 from the connection with the globe.

Mounting ears 15 extend from each side of the sleeve 14 and these are provided with perforations 16 through which screws 16^a may be passed for attaching the light, or 45 fixture to a part of the post, or cross piece. The sleeve terminates with an outlet box 17 which is formed integral with the sleeve. This box is provided with the usual cover 18 which is secured to the box by screws 19 and 50 the cover being provided with openings 20

to receive branch wires 21 which extend from the wires 5 to the lamp socket.

What I claim as new is:—

1. A lighting fixture comprising a lamp socket and globe-receiving head; a conduit sleeve extending from and integral with the head and having a projecting mounting ear thereon; and an outlet box on and integral with the sleeve, said socket, globe-receiving head, conduit sleeve and outlet box being in axial alinement. 55

2. A lighting fixture comprising a lamp socket and globe-receiving head; a conduit sleeve extending from and integral with the head and having oppositely placed mounting ears thereon; and an outlet box on and integral with the sleeve, said socket, globe-receiving head, conduit sleeve and outlet box being in axial alinement. 65

In testimony whereof I have hereunto set 70 my hand.
